Atty's

UNITED STATES PATENT OFFICE.

RAYMOND P. LANSING, OF MONTCLAIR, NEW JERSEY, ASSIGNOR TO ECLIPSE MACHINE COMPANY, OF ELMIRA, NEW YORK, A CORPORATION OF NEW YORK.

IGNITION APPARATUS.

Application filed March 17, 1924. Serial No. 699,834.

This invention relates to ignition systems adapted for use with internal combustion engines and its purpose is to provide improved means for advancing and retarding the spark in such a system. The principal object of the invention is to provide ignition apparatus in which the spark is advanced or retarded by rotating the distributor head and breaker mechanism with respect to the driving shaft. The rotation of the distributor head and breaker mechanism has heretofore been accomplished by rotating the outer casing carrying the distributor head in its bearing in the crank case or other support but the looseness of the bearing which must be provided for this adjustment results in inaccuracy and other defects in the operation of the mechanism because of the resulting instability of the casing, cam shaft and distributor head. These defects are overcome in the present invention by providing a fixed bearing for the driving shaft, which extends into the casing of the unit, and rotating the casing and its distributor head upon the fixed bearing or sleeve. This improvement not only provides a fixed bearing for the cam shaft but makes it possible to provide and maintain a stable support for the casing. Other advantages and objects of the invention will appear more clearly hereinafter.

The nature of the invention will be understood from the following specification taken with the accompanying drawings in which one embodiment is illustrated. In the drawings, Fig. 1 shows a top plan view of the distributor mechanism with the distributor head and rotor removed; Fig. 2 shows a vertical section on the line 2-2 of Fig. 1, showing the mounting of the distributor casing on its support.

The improved breaker distributor unit shown in the accompanying drawings is adapted for use with a six cylinder engine, the ignition circuit of which is controlled by the operation of a breaker arm 18 provided with a cam follower 19 arranged to contact with the peripheral surface of a cam 20 mounted on the cam shaft hereinafter described. The end of the breaker arm 18 carries a contact 21 which is adapted to engage a stationary contact 22 mounted on the stationary terminal plate 23. This plate 23 is connected to the ground and a condenser

26, mounted preferably on the distributor casing, as shown in Fig. 1, is connected around the contacts 21 and 22 for the purpose of absorbing the spark and providing the circuit with the proper capacity in relation to its inductance. As the cam 20 rotates during the operation of the engine, the primary circuit of the ignition system is intermittently opened and closed by the projections of the cam, thereby resulting in the creation of a current in the usual secondary circuit, which current is distributed to the spark plugs of the different cylinders of the engine by means of the rotor 31. One terminal of the secondary winding of the ignition system is connected to a brush 29 which bears on the distributor plate 30 of the rotor 31 and this plate 30 is adapted to distribute the secondary current to the contact points 32 of the distributor head 33. These contact points 32 are connected by conductors 25 to the spark plugs of the engine cylinders.

The breaker-distributor unit which is used with the system referred to above is illustrated in Figs. 1 and 2. It comprises a metallic casing 40 having a detachable bottom wall 41 and the integral top wall 42 which serves as a breaker platform. The casing 40 is mounted on a sleeve or bearing member 43 which is adapted to be fixed rigidly in the crank case 44 of the engine by means of a setscrew 45, or other suitable means. A drive shaft 46 is journaled in bushings 47 mounted in the sleeve 43 and the upper end of this shaft is recessed to form a bearing for the lower end of the cam shaft 48. The upper end of the cam shaft is journaled in a roller bearing 49 secured in a housing 50 formed in the upper wall 42 of the casing. The cam 20 for controlling the ignition circuit is mounted on the upper end of the cam shaft, being secured thereon by means of a set screw 51 which engages a recess in the upper end of the shaft. The set screw 51 has a tapered head 51a adapted to co-act with the correspondingly inclined wall of the recess in the shaft. The wall of the recess is slotted on opposite sides as shown at 52 to form four tongues 53 which are spread out by the inclined head of the set screw so that the cam is secured rigidly on the cam shaft. The cam is provided with an upper part 54 of reduced diameter which engages the hub

55 of the rotor 31, one side of the part 54 being flattened to co-act with the corresponding contour of the inner wall of the hub so that a driving engagement is formed 5 between the rotor and the cam. The rotor is formed of insulating material and a distributor plate 30 is secured thereon by means of a rivet 56. As the rotor travels around within the distributor head 33, which is 10 mounted on top of the casing 40, the end of the plate 30 passes in proximity to each of the contact points 32 of the distributor head, thereby distributing the secondary current to the engine cylinders. Connections are 15 made to the contact points through terminal plugs 58 and a central plug 59 is provided for making a connection with the brush 29 which is maintained in engagement with the distributor plate 30 by means of a spring 60.

20 The breaker arm 18 preferably has the angular form illustrated in Fig. 1. It is mounted on a pivot 61 extending upwardly from the upper wall 42 of the casing and the cam follower 19 carried thereby is maintained in engagement with the peripheral surface of the cam by means of a spring 62 connected to the arm 18 and reversely bent around the pin 61 with its outer end secured to a post 63 carried by the wall 42. The 25 post 63 extends downwardly through the wall 42, being insulated therefrom by a bushing 64 and the lower end of the post is connected by an insulated plate 65 with the terminal 66 which extends outwardly 30 through the wall of the casing 40, being suitably insulated therefrom. The electrical connection to the breaker arm is made through the terminal 66 and, as the cam 20 rotates, the circuit is completed through the contacts 21 and 22 to the adjustable terminal 67 carried by the plate 23. This plate is mounted on the insulating plate 68 carried on the wall 42. The condenser 26 may preferably be mounted in a recess 69 in the side 45 of the casing.

For the purpose of securing an automatic advance of the spark during the operation of the engine by changing the relative positions of the cam and rotor with respect to 50 the drive shaft, means are provided for automatically rotating the cam shaft with respect to the drive shaft 46. For this purpose the shaft 46 has a plate 70 secured to the upper part thereof and two weights 71, 55 of laminated construction, are pivotally mounted on this plate on pins 72. A cross bar 73 is secured to the cam shaft between the outer laminations of the weights 71 and the outer ends of this cross bar are pivotally 60 connected by links 74 to pins 75 which are secured to the weights and which extend downwardly through elongated openings 76 in the lower plate 70. The lower ends of these pins 75 are connected by coil springs 65 77 to other pins 78 which are secured to the

plate 70. These springs tend normally to hold the weights 71 in their inner positions, but as the speed of the engine increases the weights move outwardly by centrifugal force about the pins 72 to an extent which is limited by the elongated slots 76 engaged by the pins 75. As the speed decreases, the springs 77 return the weights toward their inner positions. As the weights move outwardly the links 74 turn the cross bar and thus rotate the cam shaft with respect to the drive shaft to effect an advance of the spark and, when the weights move inwardly, the spark is retarded.

The manual advance of the spark which is effected by rotating the casing and the distributor head with respect to the fixed bearings 43, as heretofore indicated, is brought about through an adjustable connection between the lower wall 41 of the casing and the upper portion of the sleeve or bearing 43. The member 43 is provided at its upper end with an annular flange 80 which engages the upper surface of the wall 41. A washer 81 is mounted around the shaft 46 above the flange 80 and a spacing collar 82 is mounted between this washer and the plate 70 heretofore described. The lower wall 41 of the casing is maintained in contact with the flange 80 by means of an annular spring 83 washer 84 which is located on the under side of the casing and concaved downwardly from its upper side with the central depressed portion thereof engaging a collar 85 which is mounted around the sleeve 43 and secured in position thereon by means of a split locking ring 86 seated in complementary depressions formed in the collar 85 and in the member 43. The spring washer 84 maintains a close frictional engagement of the lower wall 41 with the member 43 and the annular flange 80 so that the casing 40 and the distributor head are maintained in a stable position on their support but the wall 41 is capable of being moved between the flange 80 and the spring washer 84 when the casing 40 is turned through suitable operating connections extending to the arm 87 which projects laterally from the lower part thereof, as shown in Figs. 3 and 4. The extent of this angular movement is limited by a pin 88 which extends upwardly from the wall 41 to engage a notch 89 formed in the flange 80. When the casing 40 and the distributor head are turned, the spark is advanced or retarded due to the change in the position of the contact points of the distributor head and of the breaker arm carried by the upper wall of the casing.

Although I have shown and described one form of the invention for purposes of illustration, it will be understood that it may be constructed in various other embodiments without departing from the scope of the appended claims.

I claim:

1. A breaker-distributor unit for an ignition system comprising a casing, a supporting sleeve mounted in fixed position and extending through the wall of said casing, said sleeve having an annular flange engaging the inner surface of said wall, and an annular resilient member secured to said sleeve and engaging the outer surface of said wall opposite said flange.

2. A breaker-distributor unit comprising a casing, a supporting sleeve mounted in fixed position and extending through a wall of said casing, said sleeve having an annular flange engaging the inner surface of said wall, a spring washer extending around said sleeve and engaging the outer surface of said wall opposite said flange, and means includ-

ing a locking ring for detachably securing said spring washer in position.

3. A breaker-distributor unit comprising a casing, a supporting sleeve mounted in fixed position and extending through a wall of said casing, said sleeve having an annular flange engaging the inner surface of said wall, a spring washer extending around said sleeve and engaging the outer surface of said wall opposite said flange, means including a locking ring for detachably securing said spring washer in position, a driving shaft extending upwardly through said sleeve, and circuit-interrupting and current-distributing mechanism carried by said casing and actuated by said shaft.
